UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

METHOD OF AND MACHINE FOR LINING THE FLANGES OF CAN ENDS.

Application filed October 13, 1923. Serial No. 668,267.

This invention relates to a machine for lining the flanges of can covers, or the like, with material adapted to form a gasket, such as is commonly employed in the seam 5 by which the cover is secured to the can body.

It will be understood that the purpose of the gasket is to provide an hermetic seal and that gaskets of one form or another are necessary in practically all containers for food products and like contents. A very 10 usual form of gasket is a paper ring formed and positioned in the flange of the can cover prior to the attachment of the latter to the can body. This form, however, is not entirely satisfactory for all purposes and, of late, it has become quite a common practice to line the cover flanges with a semi-liquid compound which is deposited upon the cover 15 flange in plastic state and is dried by suitable means while adhering to said flange. In the past, said compound has usually been applied by means of a dispensing nozzle 20 positioned above the cover flange and adapted to deposit said compound in the flange as the cover is rotated, or by means of a revolving disk adapted to bear against the side of the flange and, through a scraping action, to deposit the compound in said 25 flange. These methods have not been found entirely satisfactory, either from the standpoint of production or of the results obtained, since the time required for the nozzle, or disk, to traverse the cover flange is 30 too great and, furthermore, no provision is made for the special formation of the liner, as is desirable in certain forms of containers.

The present invention is directed to an improvement in apparatus and in the method 40 of lining can ends with compound which contemplates the use of a lining die adapted to line the entire flange at a single stroke and with exactly the desired quantity of compound, which may vary at different 45 points in the flange. In this manner, a great saving of time is effected and the form of the gasket produced may be better suited to the effective sealing of particular forms 50 of covers.

Another object of the invention is the provision of a simple and efficient apparatus for the purpose stated which involves relatively few operating elements and is adapted

for extremely rapid production with minimum danger of breakage, or becoming out of repair.

A still further object of the invention is the provision, in a machine of this character, of means for regulating the thickness of the gasket in accordance with particular requirements so that not only is the peripheral form of said gasket accurately defined, but the thickness may be controlled with such nicety that the finished gasket may be 35 clean-cut and exactly of the form and quantity of material required.

Numerous other objects and advantages of the invention will be apparent as it is better understood from the following description, which, taken in connection with the accompanying drawings, discloses a preferred embodiment thereof.

Referring to the drawings,

Figure 1 is a side elevation of the machine, partially broken away for convenience in illustration;

Fig. 2 is a side elevation taken from the opposite side of the machine, with the pulley removed;

Fig. 3 is a plan view of the machine;

Fig. 4 is also a plan view with certain of the parts partially broken away and with the feed bar retaining unit folded back for better illustration;

Fig. 5 is a longitudinal section taken substantially along a central line;

Fig. 6 is an end view of the machine;

Fig. 7 is a detailed sectional view of the magnet retaining chamber, being taken substantially along the line 7-7 in Fig. 3;

Figs. 8, 9 and 10 are enlarged partial sections of the compound tank and applying die, the latter being shown in the respective figures in the positions assumed thereby at successive stages of the lining operation;

Fig. 11 is an enlarged partial plan view of the under side of a can cover lined in accordance with my invention;

Fig. 12 is a partial plan view of the lining die on the same scale as Fig. 11;

Figs. 13 and 14 are still further enlarged views, taken substantially on the section lines 13-13 and 14-14, respectively, of Fig. 11; and

Figs. 15 and 16 are partial sectional views on the same scale as Figs. 13 and 14, being

taken substantially on the section lines 15—15 and 16—16, respectively, of Fig. 12. The machine shown on the drawings, for purposes of illustration, is supported from the floor by means of a frame comprising an upper table portion 21 and legs 22 and 23. The top of the table portion 21 is preferably smoothly finished and provides a guideway for the covers as they are moved to the lining station. Side guides 24 and 25 are positioned on the top of the table and are spaced apart a distance approximately equal to the width of the can covers to be lined. A cover feeding mechanism is superimposed upon the table and comprises primarily a retaining member 26 provided with integral rearwardly extending arms 27 and 28 which are pivoted at 29 and 31 to brackets 32 and 33 secured to the frame at the opposite sides of the table, said retaining member being slotted to receive a feed bar 34 which is adapted to be reciprocated to successively deliver the covers to the lining station. The assembly just described is adapted to be turned about the pivots 29 and 31 when it is desired to get at the portion of the table underneath, but is normally held at such height above the table as to permit a cover to pass therebeneath under the influence of the feed bar 34. Screws 35 and 36 are employed to hold said assembly at the desired position, these screws extending through bosses 37 and 38 formed at the rear of the retaining member 26 and taking into holes 39 and 41 in the table 21 (see Figs. 3 and 4).

The covers are positioned in any manner, and in the present illustration by hand, between the guides 24 and 25, with their inner sides and the curl downward, and upon being moved into the sphere of action of the feed bar 34, are engaged by pivoted dogs 42, which are secured in slots 43 formed at intervals in the under side of said bar. The bar is reciprocated by means of mechanism shown clearly in Figs. 1, 5 and 6.

Forward projections 44 are provided on the rear supporting legs 23 and support bearings 45 and 46 for a cam shaft 47 and also bearings 48 and 49 for a lever shaft 51. Upon one end of the cam shaft 47 there is mounted a crank 52, which is secured by means of a screw 53 to a connecting rod 54, which latter is formed with rack teeth 55 in the upper part thereof, which mesh with a pinion 56 on a transverse shaft 57 having bearings at 58 and 59 in the pivoted arms 27 and 28. Said pinion and rack are held in mesh by means of a retaining member 61 mounted on said shaft 57 between the bearing 58 and an outer collar 62. Said member forms a housing for the pinion 56 and is slotted to permit movement of the rack bar 54 therethrough, as clearly as shown in Fig. 1.

Centrally mounted upon the shaft 57 is a spur gear 63, which extends through an opening 64 in a raised portion 65 of the retaining member 26 and meshes with rack teeth 66 formed in the rear upper face of the feed bar 34. It will be obvious that, when the shaft 57 is rocked by the described mechanism, the bar 34 will be reciprocated and will carry the can covers to successive positions of rest upon the table 21. A suitable guideway for said feed bar is provided by means of ledges 67 extending inwardly beneath a slot 68 formed in the central portion of the retaining member 26. The dogs 42 extend downwardly between the ledges 67 and are normally disposed in position to engage behind a can cover positioned between the guides 24 and 25, being, however, movable about their pivots to prevent returning movement of the covers upon the rearward reciprocation of said feed bar.

The cam shaft 47 is driven through the medium of a pulley 69 mounted on the outer end thereof and adapted to receive power from any suitable source. Rotation of said shaft serves to rock the shaft 57 and reciprocate the feed bar 34 whereby the covers are fed first to an idle station, then to a lining station and thereafter to another idle station, from which they are moved to a point of discharge.

At the lining station, I provide a plurality of electro-magnets 71 positioned in a retaining chamber 72 disposed above said lining station, said magnets being held in place by means of connecting plates 73 and studs 74. When the cover reaches the lining station, it is securely held against the under side of the retaining member 26 by the magnetic attraction of said electro-magnets 71. This insures not only that the cover will be positively held in place, but that it will present a level surface upon which the compound may be placed by the operation of the lining die to be presently described.

A tank 75 is formed in the table 21 at the lining station and is adapted to contain a quantity of semi-liquid compound fed thereto through a filling cup 76, or in any desired manner. A lining die 77 is positioned within said tank and is of the form of the can cover to be lined, being mounted upon a short shaft 78 journaled in a stuffing box 79 in the bottom of the tank 75. Inwardly extending arms 81 extend from the sides of said die to a hub 82 which is mounted upon said shaft 78. The shaft 78 is adapted to be raised and lowered by means of a cam mechanism shown clearly in Figs. 5 and 6.

A link 83 connects the lower end of said shaft 78 with an arm 84 of a bell crank lever 85 mounted on the lever shaft 51, the upper arm 86 of said lever carrying a cam following roller 87 which is held in contact with the periphery of a cam 88 mounted on the

cam shaft 47. This contact is maintained by means of a spring 89 secured at one end to the lever arm 86 and at the opposite end would be extended to one of the legs 23 (Fig. 6). It will be obvious that rotation of the shaft 47 causes the die 77 to be lifted, through the described mechanism, and it should be noted that the upward movement of this die is synchronized with the cover 10 feeding mechanism so that the die is brought into operative position at the proper time to line the flange of a cover while the latter is at rest at the lining station. As said die is lifted out of the compound, it carries on 15 its top surface a predetermined amount of said compound governed by the thickness and shape of the die and the consistency of the compound. Furthermore, the thickness of the liner, or gasket, may obviously be regulated in accordance with the height to which the die is lifted.

Referring now to Figs. 11 to 16, inclusive, it will be observed that I have shown, in the present instance, a die of oblong form adapted 25 to line the covers of sardine cans, or the like. It has been found in practice that there is a tendency, when the ordinary methods of lining (which have been hereinbefore referred to) are employed, for the lining material at the corners of the cover flange to become displaced so that an insufficient quantity remains for adequately sealing the cover to the body at these points. I have, therefore, provided a form of die in which the 30 corner portions 91 are thicker than the side and end portions 92 and 93. This results in the application of an excess quantity of compound at the corners of the cover flange, as shown clearly in Figs. 11, 13 and 14 so that 35 when the cover, which I have indicated by the reference character 94, is seamed to the can body, there will remain sufficient lining material to form a proper seal at the corners. The width of the gasket at the sides and 40 ends is indicated by the reference character 95 in Fig. 13 and the width at the corners is indicated by the character 96 in Fig. 14, these figures corresponding respectively in scale to Figs. 15 and 16 showing the different widths 45 of the die at the points indicated by the lines 15-15 and 16-16 in Fig. 12. It should be noted also that the top surface of the die may be slightly concave, in order to assist 50 in holding the compound thereon.

The compound employed for this purpose is frequently quite elastic and sticky and it has been found that after it has been applied, there is a tendency for it to stretch out, forming a web between the liner in the 55 flange of the cover and the material which remains on the top of the die as the latter recedes. This web tends to form a pocket between the under side of the cover and the surface of the compound in the tank and to 60 break the vacuum which would otherwise be

formed in said pocket, I provide vent pipes 97 and 98 extending up from the base of the tank.

In order to break the web hereinbefore referred to and which is indicated by the reference character 99 in Fig. 10, there is provided an annular air pipe 101, which is perforated on its inner side, as indicated at 102, so that compressed air, directed into said pipe, will be projected through the perforations and will puncture the web which thereupon, as has been found in practice, will settle back, leaving sufficient compound to form a gasket upon the flange of the cover. While the compressed air for this purpose may be supplied in any desired manner, I preferably employ a pump 103, which is secured at the side of the frame and which is operated as will now be described. A piston 104 is mounted on a piston rod 105 which slides in a bearing 106 secured to the rear of the pump and is connected by links 107 to a lever 108 mounted on the lever shaft 51 adjacent the bearing 49. Said lever 108 is actuated by a cam 109 mounted on 10 the cam shaft 47 and acting upon a cam following roller 111, which is held in contact with the cam surface by means of a spring 112 connected at one end to the lever 108 and at the opposite end to the frame, as indicated at 113. Reciprocation of the piston rod, 105 serves to compress the air within a chamber 114 in the pump 103, an opening 115 being provided in the wall of the pump for the purpose of admitting the air to be compressed. A head 116 is formed on the end of the pump opposite that to which the bearing 106 is secured and said head is provided with a recess, as indicated at 117. Said recess is communicably connected by means 15 of a pipe 118 with the annular pipe 101 and an opening 119 is provided in the wall between said recess and the chamber 114 of the pump. A valve 121 is normally held against a seat 122 formed in said wall about the opening 119 by means of a coil spring 123, which is mounted on a valve stem 124 and held under proper tension by means of an adjusting nut 125. This tension is such as to normally hold said valve in closed position so that air will be prevented from entering the chamber 114 upon the return stroke of the piston. This obviously serves to prevent the drawing in of air through the apertures 102 upon said return stroke. A rearwardly extending projection 126 is formed on the valve member 121 and is adapted to be engaged by a forward extension 127 on the piston rod 105 at the end of the compression stroke of said piston. This, of course, unseats the valve and causes the air to be directed through the pipe 101 and out through the perforations 102. The jets thus produced readily puncture the web 99, with the result heretofore stated.

In order to prevent the operation of the lining die when no cover is in position to be lined, I provide a device, shown clearly in Figs. 4 and 5. Said device consists of a finger 128 normally disposed in the path of the covers and pivoted at 129 to a standard 131 projecting upwardly from the bottom of the tank 75. Said finger is normally held in its upper position by means of a coil 132 engaging the under side thereof and being wound around the pivot member 129. A downward extension 133 of the finger 128 is notched at 134 and adapted to normally engage a shoulder 135 on one of the arms 81 of the die 77 when the latter is lifted. If, however, a can cover be in position at the lining station, it bears upon the finger 128 and throws the extension 133 out of the path of said arm 81. In the event that no cover is present, the die 77 is only raised a sufficient amount to engage the shoulder 135 in the notch 134 of said finger extension 133 and is then held in fixed position. The bell crank lever 85 is, of course, also held in fixed position, this being possible by reason of the stretching of the spring 89 which permits the cam following roller 87 to leave the surface of the cam 88.

Resilient fingers 136 are disposed in recesses 137 in the side guides 24 and 25, and are normally projected into the path of the covers. They are curved, as shown in Fig. 4, so that they will be forced into the recesses 137 by the covers when moving in forward direction, and will thereby frictionally hold said covers to prevent return movement with the return of the feed bar 34.

My method and mechanism therefore greatly accelerate the lining of can ends, because the die can be reciprocated so rapidly, and it is always, on an upward movement, fully charged with compound, so that a momentary touch will evenly and accurately imprint the can end with the desired amount of compound and in exactly the right place for the best hermetic sealing; the die being fully immersed in the compound after each applying stroke, and at all times when can ends are not fed, never permits any partial hardening or accumulation of compound on its imprinting or die edge, so that the die always applies the compound accurately and in desired amount; the compound does not have to pass through a restricted opening, and may be made with less solvent therein so as to be thicker and heavier, and the lined can ends require less drying; and a complete continuous and endless line of sealing material all around the can end can be imprinted at one stroke.

It is thought that the invention and many other of its attendant advantages will be understood from the foregoing description, and it will be apparent that various changes may be made in the form, construction and

arrangement of the parts without departing from the spirit and scope of the invention, or sacrificing all of its material advantages, the form hereinbefore described being merely a preferred embodiment thereof.

70

I claim:

1. A gasket lining machine, comprising means for delivering flanged can covers to a lining station, and a substantially annular continuous die member reciprocable upward and downward relative to a cover to be lined, and from a supply of lining compound, to apply a gasket to the cover flange.

75

2. A gasket lining machine, comprising means for delivering flanged can covers to a lining station, and means for applying a lining compound to the entire flange area to be lined and in varying amount in different portions of said flange.

80

3. A gasket lining machine, comprising cover feeding mechanism, means for holding a cover in position to be lined at a lining station, a tank adapted to contain a supply of semi-liquid compound, and an annular lining die of the shape and size of the desired gasket normally immersed in said compound and adapted to be moved to position depositing the compound in the flange of said cover.

85

4. A gasket lining machine, comprising cover feeding mechanism, means for holding a cover in position to be lined at a lining station, a tank adapted to contain a supply of semi-liquid compound, and an annular lining die normally immersed in said compound and adapted to be reciprocated upward and downward and to a position depositing the compound in the flange of said cover.

90

5. A gasket lining machine, comprising cover feeding mechanism, means for holding a cover in position to be lined at a lining station, a tank adapted to contain a supply of semi-liquid compound, and a lining die normally immersed in said compound and adapted to be lifted reciprocated upward and downward and to a position depositing the compound in the flange of said cover, said die being formed to carry predetermined variable amounts of compound on the different portions thereof.

95

6. A gasket lining machine, comprising cover feeding mechanism, means for holding a cover in position to be lined at a lining station, a tank adapted to contain a supply of semi-liquid compounds, and an annular lining die normally immersed in said compound and adapted to be reciprocated upward and downward and to a position depositing the compound in the form of a gasket in the flange of said cover, said cover feeding mechanism and said lining die being synchronized in operation.

100

7. A gasket lining machine, comprising cover feeding mechanism, means for holding

105

130

5 a cover in position to be lined at a lining station, a tank adapted to contain a supply of semi-liquid compound, and an annular lining die normally immersed in said compound and adapted to be reciprocated upward and downward and to a predetermined height to form a gasket of desired thickness in the flange of the cover.

10 8. A gasket lining machine, comprising means for holding a can cover at a lining station, a tank adapted to hold a supply of semi-liquid compound, a lining die normally immersed in said compound and reciprocable toward and from the cover to be lined, and means for breaking a web of compound which tends to form between the cover flange and receding die.

20 9. A gasket lining machine, comprising means for holding a can cover at a lining station, a tank adapted to hold a supply of semi-liquid compound, a lining die normally immersed in said compound and movable toward and from the cover to be lined, and means for breaking a web of compound which tends to form between the cover flange and receding die, said last-mentioned means comprising mechanism for directing compressed air into said web at spaced points.

25 10. A gasket lining machine, comprising cover feeding mechanism, means for holding a cover in position to be lined at a lining station, a tank adapted to contain a supply of semi-liquid compound, a lining die normally immersed in said compound and adapted to be lifted to position depositing the compound in the flange of said cover, and means for preventing the operation of said die when no cover is in position to be lined.

40 11. A compound lining machine for the lining of can ends, comprising means for supporting the ends to be lined, a source of lining compound arranged below said supporting means, and means for carrying the compound from said source and positively applying it simultaneously in annular form to all parts of the flanged area to be lined.

45 12. A compound lining machine for the lining of can ends, comprising means for supporting and holding from turning the ends to be lined, a source of lining compound arranged below said supporting means, and means comprising a die having the annular shape and size of the part to be lined for carrying the compound from said source and positively applying it simultaneously to all parts of the flanged area to be lined.

50 13. In a compound lining machine for lining can ends, the combination of means for applying compound to can ends, and means for attracting and moving the can ends to the plane at which the compound is applied at once to all desired parts of the can ends.

14. In a compound lining machine for lining can ends, the combination of means for applying compound to can ends, and magnetic means for causing the can end to coincide with the plane at which the compound is applied at once to all desired parts of the can ends. 70

15. In a compound lining machine for lining can ends, the combination of a source of lining compound, a die having an annular contour corresponding with the parts of the can end to be lined, the width of the operative face of the die corresponding at all parts with the desired width of the compound when applied to the can end, means 75 for feeding can ends into position above the die to receive the compound, and means for moving the die alternately from the compound to the can end to apply a complete gasket at one stroke, and then to a position 80 immersed in the compound so that drying and excessive collecting of compound on the die is prevented. 85

16. In a compound lining machine for lining can ends and forming gaskets thereon, the combination of a source of lining compound, a die having a contour corresponding with the parts of the can to be lined, the width of the operative face of the die corresponding at all parts with the desired width of the compound when applied to the can end, means for holding can ends in position above the die to receive the compound, means for moving the die alternately 90 from the compound to the can end to apply a complete gasket at one stroke and then to a position 100 immersed in the compound so that drying and excessive collecting of compound on the die is prevented, and means for causing the can end to coincide with the plane at which the compound is applied so as to receive a complete and sufficient gasket of the compound. 105

17. The combination of a die having an operative face adapted to extend around the shoulder of a can end and to place a gasket of compound on the flange at one impression, a source of compound supply, means for holding the can end in position to have the compound imprinted thereon by said die, and means for reciprocating the die from the source of compound to the can end and thence to the compound. 110 115

18. In a compound lining machine for lining can ends, the combination of a source of lining compound, a die having an annular contour corresponding with the parts of the can to be lined, the width of the operative face of the die corresponding at all parts with the desired width of the compound when applied to the can end, means for holding can ends in position above the die to receive the compound, and means for moving the die alternately from the compound to the can end to apply a complete 120 125 130

- gasket at one stroke and then to a position immersed in the compound so that drying and excessive collecting of compound on the die is prevented.
19. In a compound lining machine for lining can ends, the combination of a source of lining compound, a die having a contour corresponding with the parts of the can to be lined, the width of the operative face of the die corresponding at all parts with the desired width of the compound when applied to the can end, means for feeding can ends into position above the die to receive the compound, means for moving the die alternately from the compound to the can end to apply a complete gasket at one stroke and then to a position immersed in the compound so that drying and excessive collecting of compound on the die is prevented,
- 20 and means for preventing the operation of said die when no can end is in position to be lined.
20. In a compound lining machine for lining can ends and forming gaskets thereon, the combination of a source of lining compound, a die having a contour corresponding with the parts of the can to be lined, the width of the operative face of the die corresponding at all parts with the desired width of the compound when applied to the can end, means for holding can ends in position above the die to receive the compound, means for moving the die alternately from the compound to the can end to apply a complete gasket at one stroke and then to a position immersed in the compound so that drying and excessive collecting of compound on the die is prevented, means for causing the can end to coincide with the plane at which the compound is applied so as to receive a complete and sufficient gasket of the compound, and means for preventing the operation of said die when no can end is in position to be lined.
21. In a compound lining machine for lining can ends, the combination of a source of lining compound, a die having a contour corresponding with the parts of the can end to be lined, the width of the operative face of the die corresponding at all parts with the desired width of the compound when applied to the can end, means for holding can ends in position above the die to receive the compound, means for moving the die alternately from the compound to the can end to apply a complete gasket at one stroke and then to a position immersed in the compound, so that drying and excessive collecting of compound on the die is prevented, and a hinged frame adapted to be lifted and carrying the said means for holding the can ends.
22. The method of lining can ends which consists in positioning a can end with its inner side downward above a body of lining compound and elevating from said compound to said can end, an amount of compound sufficient for a gasket and imprinting said amount of compound at the same time as a complete gasket on the can end outside of the shoulder and on the flange of said can end, and causing it to adhere thereto. 65
23. The method of lining can ends which consists in positioning a can end with its inner side downward above a body of lining compound, attracting said can end upward and holding it from further upward movement, and elevating from said compound to said can end an amount of compound sufficient for a gasket and imprinting said amount of compound at the same time as a complete gasket on the can end, and causing it to adhere thereto. 70
24. The method of lining can ends which consists in positioning a can end with its inner side downward above a body of lining compound, attracting said can end upward and holding it at a certain level, sliding the can end horizontally to compound-receiving position, and elevating from said compound to said can end, an amount of compound sufficient for a gasket and imprinting said amount of compound at the same time as a complete gasket on the can end, and causing it to adhere thereto. 80
25. The process of lining can ends which comprises positioning can ends with their inner sides downward, providing a bath of lining compound, and removing from said bath upward to the can end a compound member in the annular shape of a gasket and depositing the same in said shape on to the flange of the can end. 95
26. A gasket lining machine, comprising means for delivering flanged covers to a lining station and a member shaped to pass about the shoulder of the can end to deposit compound upon the flange above said shoulder. 100
27. In a compound lining machine for lining can ends and forming gaskets thereon, the combination of a source of compound, means for arranging a can end above said source with its inner side downward, a die member formed to pass about the shoulder of the can end and adapted to convey lining material upward from said source to the flange of said end and above said shoulder and means for moving said die member upward from said source of the under side of said can end. 110
